CLAIM

The ornamental design for a shirt pocket as shown and described.

DESCRIPTION

FIG. 1 is a perspective view of a shirt pocket showing my new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a perspective view of the shirt pocket showing my new design in use for carrying articles.

In the drawings, the broken lines represent unclaimed environment subject matter and form no part of the claimed design.

In the drawings, the small broken lines indicative of stitching form no part of the claimed design.

1 Claim, 6 Drawing Sheets
